UNITED STATES PATENT OFFICE.

HERBERT JAY TRAVIS, OF CORNING, NEW YORK, ASSIGNOR TO CORNING GLASS WORKS, OF CORNING, NEW YORK, A CORPORATION OF NEW YORK.

SKIMMING MEANS FOR TANK FURNACES.

1,410,782.

Specification of Letters Patent. Patented Mar. 28, 1922.

Application filed November 19, 1920. Serial No. 425,120.

To all whom it may concern:

Be it known that I, HERBERT J. TRAVIS, a citizen of the United States of America, and a resident of Corning, in the county 5 of Steuben and State of New York, have invented certain new and useful Improvements in Skimming Means for Tank Furnaces, of which the following is a specification.

10 This invention relates to furnaces, and more particularly to furnaces adapted to be used for melting metal. In the present instance, as illustration of an embodiment of my invention, I have chosen to show the 15 same applied to tank furnaces, such as are in general use today for the purpose of melting glass.

Heretofore, in the construction of glass tank furnaces it has been the custom to contract each of the opposite side walls thereof to leave a single or double spout walls, which latter are surrounded by atmosphere or other means of cooling. Thus large notches are formed in the side walls of the 25 tanks, and during the operation thereof, these notches cause considerable trouble, owing to their weakness of construction. Furthermore, in order to provide means for cooling the spout walls, that extend across 30 the walls of the interior of the tanks from the notches on one side to the notches on the opposite side, it is necessary to make these notches with large open spaces therebetween, whereby air can pass freely around, for the 35 purpose of lowering the temperature of the spout walls.

When this form of construction is used, the spout walls connecting the throats formed in the tanks by the notches, usually 40 consist of floating members, that are placed between the contracted openings between the rear, or melting portion of the tanks, and the front or working end thereof. As the notches formed in the side walls extend 45 from the bottom of the tanks towards the roof thereof, the tanks are divided substantially into two chambers, which are closed by bridges forming the spout wall. As these bridges are constructed so that they 50 cannot move laterally but are free to move upwardly and downwardly, and as they are somewhat buoyant, they are supported by the molten glass in the tank. The buoyancy of the floating bridges, is 55 usually such, that their upper surface projects

slightly above the level of the molten glass, and they therefore act as skimmers for the impurities present adjacent the surface of the glass, that is in the melting end of the tanks, and in this manner such impurities 60 are caught by the bridges and prevented from passing into the working end of the tanks. The bridges are usually formed of refractory material capable of withstanding the intense heat and chemical action of 65 the molten glass, and in order to make this refractory material buoyant, it has been the custom to make them of some porous material.

There are several disadvantages in utilizing floating bridge walls for glass tanks, as in some instances the bridges will absorb 70 sufficient molten glass to obliterate their buoyancy, and this causes them to sink to the bottom of the tank, thereby destroying 75 their purpose. In other instances, when floating bridge walls are used, and when the level of the glass in the tanks has been reduced somewhat, and then raised, the bridges are caught in their guideways, and 80 prevented from rising with the molten glass when such level rises.

To overcome the above mentioned difficulties, I propose to construct a glass tank with its spout-wall notches eliminated, and 85 in lieu thereof, provide a spout wall extending the entire width of the tank. In the embodiment of my invention that I have herein illustrated and described, a tubular bridge is fixedly secured to the side 90 walls of the tank, and positively positioned therein. This bridge provides a passage for the molten glass that extends the entire width of the tank and it is of sufficient diameter or cross-sectional area that it serves 95 the purpose of a skimmer for the molten glass, whether its level be low or high, and means are also provided for supporting the tubular bridge in the tank.

In the description to be hereinafter given, 100 while the term "tank" is used, it is to be understood that such name is chosen only for the sake of brevity, and that my invention and application can equally as well be adapted to other types of furnaces other than the 105 one illustrated, and that the work "tank" includes any structure used to heat and prepare metals for the purpose of working the same.

In order that other persons skilled in the 110

art to which my invention appertains, may make and use the same, I will now describe a practical form of structure falling within its scope.

5. In the drawings accompanying this application and forming part thereof:—

Figure 1, is a horizontal section through a glass tank having a spout wall constructed in accordance with my invention;

10. Fig. 2, is a vertical longitudinal section through the tank shown in Fig. 1, showing the spout wall in transverse section.

Fig. 3, is a section, taken on the line 3—3, of Fig. 1, showing the spout wall in longitudinal section.

Figs. 4 and 5, are detail views of one of the disks forming the spout wall; and

Figs. 6, 7, and 8, are detail views of the supporting means for disks.

20. Referring to Figs. 1 and 2, of the drawings, I have shown a conventional form of tank furnace suitable for use in melting glass. The tank 10, consists of a rectangular chamber having parallel side walls 11, and 25 a semicircular front wall 12, which walls, a suitable distance above the bottom of the tank, are arched to form a roof 13. The front wall 12, may be provided with any number of boot-openings, that are for the 30 purpose of permitting workmen to make gathers from the molten glass in the tank, and this end of the tank is usually known as the working end.

The melting end of a glass tank is usually 35 of somewhat greater area than the working end, because the materials from which the glass is formed melt rather slowly, and it therefor, requires considerable time to prepare such materials before the molten glass 40 is in a workable condition. With this in view, I propose to install a skimming spout or bridge wall, that is positioned in the tank nearer to the working end, than to the melting end. As illustrated, this skimming 45 spout consists of a tubular member 15, that extends the width of the tank, and which is also placed a suitable distance above the bottom thereof.

The tube 15 is preferably formed of disk- 50 like blocks 16, made from refractory material that will resist the chemical action of molten glass, the kind of material depending, of course, upon the kind of glass, as various materials are attacked differently 55 by various ingredients in molten glass. Each of the blocks 16, are similar in form and design, and, as illustrated by Figs. 4 and 5, of the drawings, the blocks have formed therein a central bore 17, that provides an 60 opening which is coextensive with the width of the tank, when the blocks are assembled therein. The faces of each of the blocks are provided with beads or tongues 18, and grooves 19, that are formed alternately 65 thereon, whereby the tongues will engage

in the grooves, and thus provide means by which the blocks are interlocked when assembled, so that they will be prevented from being misplaced as will be readily understood.

70. The blocks are so designed that they form a substantially unitary structure that will function properly in any type or design of tank, and these blocks may be of any desired diameter, depending of course upon the size 75 of the tank, and the depth at which the molten glass is maintained therein.

For the purpose of installing supporting and cooling means for the tube, openings 20, of approximately the same diameter as the 80 size of the central bore 17, of the blocks, are formed in the side walls of the tank, in registration with the bore of the tube, and a pipe 21 is positioned within the bore 17, and this pipe has its ends projecting through the 85 openings 20. Brackets 22 mounted upon the exterior of the walls of the tank and having an annular portion 24 which is fitted to the openings 20, and a recessed head 25 into which is inserted the ends of the same, serves 90 as means for supporting the pipe 21. The recessed heads 25 of the brackets are spaced from the annular portions 24 thereof, by means of radially extending arms 26. Through apertures 27 centrally located in 95 each head 25 of the brackets is passed a tie rod 28, having a head on one end, and its opposite end threaded for the reception of a nut. An expandable spring 29 is interposed between the nut on the threaded end of 100 the tie rod and the head of the bracket, for the purpose of permitting the various parts of which the tube is composed, to expand and contract without collapsing, as will be readily understood.

105. The diameter of the pipe 21 is somewhat less than the diameter of the central bore 17, and formed on the exterior of the former, intermediate its ends, are radially extending pins 33 that are adapted to act as supports 110 for the blocks 16, of the tube. The pins 33 are arranged in staggered relation whereby three or more of them will engage the central bore 17, of each block and as all are of the same length, the construction permits of 115 the pipe to be centrally disposed within the bore. Each end of the pipe 21, is provided with a plurality of slots or openings 30 which are located in the protruding ends of the pipe between the annular portions 24 120 and the heads 25 of the brackets 22.

As shown by Fig. 3, the method of supporting the pipe within the tube, provides two independent air spaces, one being exterior of the pipe 21, while the other is 125 interior the pipe 21. The air in the space exterior of the pipe will absorb heat conducted through the blocks from the molten glass that partially surrounds them, while the air in the space within the pipe will absorb the 130

- heat radiated by such pipe. To maintain the temperature within the tube below that of the molten glass and also to keep the blocks 16, as cool as possible, so that the molten glass surrounding the tube will be chilled sufficiently to freeze the same to the outer surface of the blocks, a hood 31, having one end enclosing one of the pipe supporting brackets 22, and its other end open, 10 is secured to the side wall of the tank. Cool air introduced into the open end of the hood, will as shown by the arrows in Fig. 3, and 7, pass through the openings formed in the bracket, a quantity entering the the slots 15 formed in the end of the pipe within the bracket, while the remainder will pass into the space within the tube that surrounds the pipe, and as the opposite end of the tube is open, this air will circulate through the pipe 20 and tube, absorbing the radiated heat therein, and will then exhaust through the openings in the opposite end. Due to this cooling action, the molten glass will become chilled, and freeze to the submerged portion 25 of the tube. This results in additional strength being given the tube, and the coating of glass upon the blocks 16, will tend to seal the joints therebetween, thus preventing chemical action of the molten glass from eating the material of the blocks. The coating 30 of glass upon the tube will also serve as insulating means, thereby preventing the excess heat in the tank from penetrating the tube.
- 35 The diameter of the tube 15, and its position within the tank may be such that the spout wall formed thereby is of sufficient depth to prevent the passage of undesirable particles contained in the molten glass from 40 passing from the melting end of the tank to the working end thereof, whether they are floating upon or adjacent the surface thereof, when the glass is at its maximum, or at its minimum working level.
- 45 Having thus described my invention, what I claim and desire to secure by Letters Patent is:—
1. A spout wall for tank furnaces consisting of a tube composed of interlocked 50 disks.
  2. A spout wall for tank furnaces consisting of a tube composed of interlocked disks, and means for supporting the tube from the side walls of the tank.
  - 55 3. A spout wall for tank furnaces consisting of a tube composed of interlocked disks, and means for supporting the tube from the side walls of the tank, said supporting means extending through the disks 60 and being spaced therefrom.
  4. A spout wall for tank furnaces consisting of a tube composed of interlocked disks, and means for supporting the tubes from the side walls of the tank, said supporting means extending through the disks 65
- and having means for spacing the disks therefrom.
5. A spout wall for tank furnaces consisting of a tube composed of interlocked disks, means for supporting the tube from the side walls of the tank, said supporting means extending through the disks, and brackets positioned on the opposite ends of the supporting means for the purpose of securing said supporting means to the side walls of the tank.
6. A spout wall for tank furnaces consisting of a tube composed of interlocked disks, means for supporting the tube from the side walls of the tank, said supporting 80 means extending through the disks, brackets positioned on the opposite ends of the supporting means for the purpose of securing said supporting means to the side walls of the tank, and means for resiliently connecting the supporting means to the brackets.
7. A spout wall for tank furnaces consisting of a tube composed of interlocked disks, means for supporting the tube from the side walls of the tank, said supporting 90 means extending through the disks, brackets positioned on the opposite ends of the supporting means for the purpose of securing said supporting means to the side-walls of the tank, means for resiliently connecting 95 the supporting means to the brackets, and means formed in the brackets for the purpose of permitting a cooling fluid to circulate through the tube.
8. A spout wall for tank furnaces consisting of a tube composed of interlocked disks, means for supporting the tube from the side walls of the tank, said supporting means extending through the disks, brackets positioned on the opposite ends of the supporting 100 means for the purpose of securing said supporting means to the side walls of the tank, means for resiliently connecting the supporting means to the brackets, means formed in the brackets for the purpose of 105 permitting a cooling fluid to circulate through the tube, and a hood enclosing one of said brackets, said hood being designed to guide the cooling fluid towards the tube.
9. A spout wall for tank furnaces consisting of a tube composed of interlocked disks, means for supporting the disks comprising a pipe extending therethrough and projecting through the side walls of the tank, said pipe having radially extending 110 pins for the purpose of spacing the disks of the tube therefrom to provide an air space, brackets positioned on the outer walls of the tank each of said brackets having a flange for engaging the side walls of the 115 tank and a recessed headed portion spaced from said flange for the purpose of receiving the ends of the pipe, a tie-rod passing through the pipe and resiliently secured to the recessed headed portions of said brackets, 120 125 130

means formed in the ends of the pipe between the flanges of the brackets and the recessed headed portions thereof for the purpose of permitting a cooling fluid to enter thereof for the purpose of permitting a cooling fluid to enter said pipe and pass therethrough, and means formed in the brackets between the flanged portions and the recessed headed portions therethrough and around the exterior of the 10 pipe.

In testimony whereof I hereunto sign my name this 10th day of Nov., 1920.

HERBERT JAY TRAVIS.
